CLOSURE FOR STORAGE BATTERIES

Ernest H. Riedesel, Jr., Bennett, Iowa

Application May 7, 1940, Serial No. 333,860

5 Claims. (Cl. 136—177)

My invention relates broadly to new and useful improvements in closures, and more particularly to closures for storage batteries.

An important object of my invention is to provide a closure adapted to permit all of the cells of a battery to be simultaneously closed, to normally effectively seal the cells and to permit all of the cells to be simultaneously opened.

Another object of my invention is to provide a closure of the above-mentioned character which permits easy access to be had to all of the cells for internal inspection, and which greatly expedites the operation of testing and filling the cells.

Still another object of my invention is to provide a closure of the above-mentioned character which will normally be tightly held in closing relation with the battery, but which may be easily disengaged from the battery when desired, thus facilitating the servicing of the battery.

Other objects and advantages of my invention, will be apparent during the course of the following description.

In the drawing, forming a part of this specification, and wherein like numerals are employed to designate like parts throughout the same,

Figure 1 is a longitudinal sectional view of a device embodying my invention, and showing the same associated with a plurality of battery cells,

Figure 2 is a top plan view of the same,

Figure 3 is a side elevation of a modified form of the invention, and

Figure 4 is a fragmentary sectional view illustrating one of the closure plugs of my invention associated with a modified form of battery filler opening.

In the accompanying drawing, wherein for the purpose of illustration, is shown a preferred embodiment of my invention, the numeral 10 designates a conventional storage battery including a case or container 11 formed of a rubber composition, or the like, and having integrally formed transverse partitions 12 which define the separate battery cells 13. Each of the cells contains a plurality of electrodes (not shown) and is adapted to be filled with an acid solution in accordance with the common practice. The cover plates 14, formed of a hard rubber, or the like, inclose the top of each cell, and each of the cover plates is provided with a central threaded opening 15. The cover openings normally receive individual filler caps which comprise closures for the openings.

The present invention contemplates an arrangement which will permit all of the openings 15 to be easily opened or closed in a single operation and which will eliminate the necessity of separately opening each of the cells in the manner heretofore required. I have provided an elongated body 16 formed of a suitable hard rubber composition, or the like, which body is of sufficient length to extend over all of the filler openings 15 of the battery. The plugs 17 extend perpendicularly from the bottom face 18 of the body and are suitably spaced whereby each may be fitted into one of the filler openings 15. As clearly illustrated in Figure 1 of the drawing, each of the plugs is formed with an annular base portion 19 which seats against the cover plate circumjacent to the filler opening and an elongated frusto-conical-shaped portion 20. The side walls of the frusto-conical-shaped portions of the plugs are not threaded and may be formed of either hard or soft rubber but, in either event, the portions are constructed to snugly fit the filler openings. A considerable strain may be developed in the body portion when sufficient force is applied thereto to simultaneously remove all of the plugs from their respective openings, and I have, therefore, provided reinforcing metallic rods 21 imbedded in and extending longitudinally of the body.

In order to assure a normally fixed but detachable engagement of the closure with the battery I have formed one of the plugs in the manner illustrated by the central plug in Figure 1 of the drawing. The portion of the plug extending beyond the base 19 is not frusto-conical-shaped but is cylindrical in its formation and the vertical wall thereof is provided with screw threads adapted to threadedly engage its respective cell opening 15. This plug is not integrally formed on the body but extends therethrough and the portion extending thereabove has a suitable cap 22 fixedly secured thereon. The cap 22 and base 18 embrace the opposite sides of the body and permits the plug to be freely rotatable relative thereto, whereby the plug may be threadedly fitted into its respective opening. The frusto-conical-shaped plugs arranged at opposite sides of the central threaded plug may then be pressed into the other of the cell openings.

Each of the plugs is formed with a central recess 23 which opens directly through the bottom face thereof and into the battery cell. Each of the recesses is also provided with a substantially small vent 24 which opens through the

body and affords communication with the atmosphere. A baffle plate 25 is arranged transversely of the open lower end of each recess to prevent splashing of the liquid in the cells through the vents 24.

The closure hereinabove described permits access to be had to all of the cells by the simple expedient of unthreading the central plug and lifting the closure from the battery. This plug, therefore, comprises a single control means for fixedly but detachably connecting the body 16 to the battery. Unthreading of the plug will simultaneously raise each of the fixed plugs 17 out of their respective filler openings to permit ready and basic removal of the body. The trouble attendant with unthreading individual filler plugs from each of the cells is thereby eliminated and the operation of filling the cells is greatly expedited. In the past, considerable trouble has been caused by the fact that the essentially small individual filler plugs are easily lost or misplaced. The closure here illustrated may be laid to one side and, when replaced, the central plug is threaded into its respective cell opening and the other plugs pressed into their openings in a single easy operation.

Figure 3 illustrates the formation of the body 16 which may be necessary on certain types of batteries in order to avoid the terminal connections of the respective cells.

Figure 4 illustrates a battery wherein the end cell openings 15 may be unthreaded and frustoconical in shape to snugly receive the end plugs.

It is to be understood that the form of my invention, herewith shown and described, is to be taken as a preferred example of the same, and that various changes in the size, shape and arrangement of parts may be resorted to without departing from the spirit of my invention, or scope of the appended claims.

Having thus described my invention, I claim:

1. In a battery of the type having a plurality of separate cells each provided with a separate filler opening, a body having a plurality of fixed plug members snugly received by certain of the cell openings for pressed peripheral engagement with the walls of the openings, and a plug member rotatably but nondetachably carried by the

body adapted to threadedly engage another of the said cell openings, said last plug comprising a single control means for holding the body detachably connected to the said battery.

2. In a battery of the type having a plurality of separate cells each provided with a separate filler opening, a body having a plurality of fixed plug members snugly frictionally received by certain of the cell openings, a plug member rotatably but nondetachably carried by the body adapted to threadedly engage another of the said cell openings, said last plug comprising a single control means for holding the body detachably connected to the said battery and all of said plug members having a venting communication with their respective cells, and baffle elements carried by each of the plugs and arranged in semi-obturating relation to the vents.

3. In a battery of the type having a plurality of separate cells each provided with a separate filler opening, a body, handle means rotatably but nondetachably carried by the body and having a screw-threaded part engageable within one of the cell openings, and fixed plugs carried by the body adapted to be pressed into and to snugly fit the other of the said cell openings.

4. In a battery of the type having a plurality of separate cells each provided with a separate filler opening, a body, a plug rotatably but non-detectably carried by the body adapted for screw-threaded engagement with one of the filler openings, and plugs fixedly carried by the body adapted to be pressed into the other of the said filler openings.

5. A closure member for a battery having a plurality of separate cells each provided with a separate filler opening, comprising a body having lateral extensions shaped to be snugly but detachably received by each of the cell openings, one of said extensions being rotatably but nondetachably associated with the body and including a screw threaded shank portion threadedly received by one of the said filler openings, said threaded shank holding the other of the extensions in obturating relation with their respective filler openings.
